(57) **CLAIM**

The ornamental design for a shoe, as shown and described.

DESCRIPTION

FIG. 1 is a left side perspective view of an ornamental design for a shoe;

FIG. 2 is a left side view of the shoe of FIG. 1;

FIG. 3 is another left side perspective view of the ornamental design with alternative environmental structure;

FIG. 4 is a left side view of the shoe of FIG. 3;

FIG. 5 is yet another left side perspective view of the ornamental design with alternative environmental structure;

FIG. 6 is a left side view of the shoe of FIG. 5;

FIG. 7 is still another left side perspective view of the ornamental design with alternative environmental structure; and,

FIG. 8 is left side view of the shoe of FIG. 7.

The dash-dash-dash broken lines are included for the purpose of illustrating portions of the shoe that form no part of the claimed design. The contrast in color represents a contrast in appearance only.
